UNITED STATES PATENT OFFICE.

WILLIAM T. SMITH, OF PHILADELPHIA, PENNSYLVANIA.

DESIGN FOR A WOVEN FABRIC.

44,386.

Specification for Design.

Patented July 22, 1913.

Application filed May 16, 1913. Serial No. 768,166. Term of patent 7 years.

To all whom it may concern:

Be it known that I, WILLIAM T. SMITH, a citizen of the United States, residing in Philadelphia, Pennsylvania, have invented a certain new, original, and ornamental Design for Woven Fabric, of which the following is a specification, reference being had to the accompanying drawing, forming part thereof, in which the figure is a plan view

of a portion of woven fabric showing my new design.

I claim:

The ornamental design for a woven fabric as shown.

WILLIAM T. SMITH.

Witnesses:

R. C. STERNER,
JNO. S. GEBHARDT.
